RUG.

No. 21,005.

Patented Aug. 18, 1891.

UNITED STATES PATENT OFFICE.

ERNEST H. BENNETT, OF EAST ORANGE, NEW JERSEY, ASSIGNOR TO JOHN BROMLEY & SONS.

DESIGN FOR A RUG.

SPECIFICATION forming part of Design No. 21,005, dated August 18, 1891.

Application filed February 2, 1891. Serial No. 379,925. Term of patent 3½ years.

To all whom it may concern:

Be it known that I, ERNEST H. BENNETT, a citizen of the United States of America, residing at East Orange, in the county of Essex and State of New Jersey, have invented a certain new and original Design for a Rug, of which the following is a specification, reference being had therein to the accompanying drawing.

10 My invention relates to the surface ornamentation of a rug; and it consists of the design therefor which is fully illustrated in the accompanying photographic drawing, and which is one half of the complete design, the other 15 half, or "repeat," as it is technically called, being precisely similar.

The leading feature of the design is the comparatively large ornamental pattern C,

which constitutes a border for the rug, and the inner lines of which are so conformed as 20 to constitute a comparatively small field center A, with an ornamental ground-work D of cross-lines placed therein, said field center also containing in its central portion the figure B.

I claim as my invention—

25 1. The design for a rug, substantially as shown and set forth.

2. The design for the enlarged border C of a rug, substantially as shown and set forth.

In testimony whereof I affix my signature in 30 presence of two witnesses.

ERNEST H. BENNETT.
